CONNECTOR PLUG

Filed Dec. 29, 1944

UNITED STATES PATENT OFFICE

2,452,967

CONNECTOR PLUG

Orrin H. Thomas, Williamsport, Pa.

Application December 29, 1944, Serial No. 570,355

2 Claims. (Cl. 173—361)

1

This invention relates to electrical connector plugs and it consists in the constructions, arrangements and combinations herein described and claimed.

It is a particular object of the invention to provide a plug having contact blades embodying a pair of resilient leg or blade members which normally are divergent with respect to each other, one leg being fixed and the other free for movement to a substantially parallel relation with the fixed leg, there being spring means for limiting excessive flexing movement of the free leg, thereby insuring a positive and firm contacting engagement with contacts of a socket when inserted therein.

It is also an important object of the invention to provide a novel construction of plug body, enabling ready assembly of the parts as well as connection of the conductor wires to respective binding posts of the plug, and also maintain the spring means in a secure position against accidental displacement.

Additional objects, advantages and features of invention will be apparent from the following description considered in conjunction with the accompanying drawing, wherein

Figure 1 is a vertical section through the plug.

Figure 2 is a cross section on the line 2—2 of Figure 1.

Figure 3 is a cross section on the line 3—3 of Figure 1.

Figure 4 is a cross section on the line 4—4 of Figure 1.

Figure 5 is a vertical section on the line 5—5 of Figure 1.

Figure 6 is a perspective view of the contact prongs and spring means detached from the plug.

There is illustrated in Figures 1 to 5 an attachment plug 10, formed of insulating material in two vertical sections 11 and 12, and as may be seen in Figures 1, 2 and 4, the section 11 is formed with a passage 13 divided longitudinally by a medial abutment 14, the inner end of which is tapered and stopping short of the conductor inlet opening 15 a distance. The wall defining the opening 15 is continued downwardly upon opposite sides of the abutment, as at 16, following the general contour of the exterior shape of the section, which is here shown as of substantial bell-shape at the lower part, merging inwardly to form a reduced neck 17 and finally terminating in an annular head 18.

A pair of openings 19 are formed in the base 20, positioned at opposite sides of the abutment 14, forming communication with respective pas-

2

sages 13. The base 20 is of substantial thickness and where the walls 16 terminate respective shoulders 21 are formed, the latter functioning for mounting of respective contact prongs 22, as will be described.

Attention is now invited to Figure 6 of the drawings, wherein the prongs 22 are illustrated, and it will be seen that the prongs are of identical construction, consisting of a pair of blades 23 and 24, formed from a single strip of metal bent intermediate its length, the blades being in divergent relation to each other. Normally, the blades are of equal lengths but the blade 23 is bent at right angles inwardly of one of its free ends to form a base mounting 25, the latter being apertured as at 26. Thus, the blade 24 is of a length greater than the blade 23 so that the blade 24 will extend a substantial distance inwardly of the opening 19, when in assembled relation within the plug, and by reason of the divergency of the blades, the blade 24 will lie against or closely adjacent the wall of the abutment 14, as may be seen in Figure 1.

The abutment 14 is formed with a pair of slots 27 extending transversely thereof, of a depth the same as the openings 19, and extending in parallel relation to the flat face of the leg 24. A pair of substantially U-shaped spring clips 28 are employed, consisting of a bight portion from which respective legs 29 are extended in parallel relation, the legs being of a thickness slightly less than the width of the slots 27 and of the same length from the inside of the bight portion of the clips, thus presenting the bight portions outwardly of the face of the section, by the thickness of the metal, for a purpose presently to be explained.

The section 12 will have a smooth planiform face longitudinally of its length, except at points next adjacent that portion opposed to the bight portions of the clips, where respective recesses 30 are formed providing seats for the bight portions of the clips. From the above construction, it will be apparent that when the prongs are in assembled relation within the sections 11 and 12, the prongs are securely held against lateral movements.

The sections 11 and 12 are each provided with a transversely extended opening 31 adapted to be in registry when the sections are in mated or aligned relation, and receive an assembly bolt and nut 32 for securing the parts together. Preferably the outer ends of the openings are countersunk so that the head of the bolt and the nut will

lie beneath the outer contour of the sections thus presenting a smooth exterior surface.

In order to assemble the prongs within the plug, it being understood that the sections 11 and 12 are in a disassembled relation, one of the prongs 22 is presented into the openings 19, with the mounting 25 presented directly upon the shoulder 21, the aperture 26 formed in the shoulder 21. A binding screw 33 is now positioned through the openings 26 and 26' so as to partly engage into the base 20. The other prong is similarly positioned and secured, and in each instance, it will be seen that the blade 24 lies quite close to or contacting respective sides of the abutment 14.

The conductor 34 is now laid within the opening 15, respective leads 35 being secured to respective binding screws 33, the latter being tightened to secure the leads 35. It is now only necessary to secure the blade 24 against excessive flexure toward the blade 23 and this is accomplished by inserting one leg 29 of the clip into the slot 27, the other leg 29 being disposed about the blade 24 tending to hold the blade against the abutment 14. The other clip is similarly engaged. The section 12 is now aligned with the section 11, the apertures 31 being in registration when the recesses 30 are in snug seating engagement upon the bight portions of the clips. The bolt 32 is inserted through the apertures 31 and secured by means of a nut.

A plug constructed as shown and described will insure a positive and firm grip within a wall receptacle or other similar fitting by reason of the fact that the contact blades 23 and 24 are maintained against excessive flexure toward each other, yet by the inherent resilience of the blades and the clips, the prongs may be readily inserted in appropriate electrical fixtures.

While I have shown and specifically described preferred forms of the plug, this is by way of illustration only, and I consider as my own all such modifications in construction as fairly fall within the scope of the appended claims.

I claim:

1. An electrical attachment plug comprising a body member of insulating material consisting of two separable sections, said sections having a conductor inlet and one of said sections having an interior passage, an abutment on said section extended inwardly upon said passage and stopping

short of the conductor inlet, a pair of openings being formed in the base of said section, positioned on opposite sides of the abutment, a shoulder inwardly of each opening, a contact prong disposed within each opening, said contact prongs comprising a pair of divergent blade members, one of said blades being bent to form a base mounting for seating engagement with respective shoulders, said base mounting and said shoulders being apertured for reception of a binding screw, the other blade of said prongs extending inwardly adjacent respective sides of said abutment, a pair of spring clips, one of which is mounted on each side of said abutment having a portion adapted to overlie respective terminal ends of said blades, said other section having recessed portions complementary to a portion of said spring clip members and said sections being provided with transverse aligned openings and an assembly bolt engaged therethrough.

2. A prong for electrical connector plugs comprising a pair of integral longitudinally divergent blade members, one of said blades having an angularly disposed apertured mounting base adapted to be engaged in a portion of a plug body, the other blade having a free end adapted to engage a portion of a plug body, and a separate spring clip member having a pair of integral parallel leg members, one of which overlies said last named blade member adjacent the free end and the other leg member being adapted to be engaged in a portion of a plug body adjacent said free end.

ORRIN H. THOMAS.
